UNITED STATES PATENT OFFICE.

EDMUND C. BATES, OF ALLIANCE, OHIO, ASSIGNOR TO THE BUCKEYE JACK MANUFACTURING COMPANY, OF ALLIANCE, OHIO, A CORPORATION OF OHIO.

LIFTING JACK.

Application filed November 8, 1920. Serial No. 422,438.

To all whom it may concern:

Be it known that I, EDMUND C. BATES, a citizen of the United States, residing at Alliance, in the county of Stark and State of Ohio, have invented a certain new and useful Improvement in Lifting Jacks, of which the following is a full, clear, and exact description, reference being had to the accompanying drawings.

10 This invention relates to lifting jacks and particularly to those suitable for raising the axles of automobiles and other vehicles, the invention being concerned with means for readily reversing the direction of movement 15 of the raising element.

Usually the toothed rack type of jacks are equipped with a trip lever for reversing the direction of travel of the rack. This trip lever is generally carried by the frame of 20 the jack and consequently is rendered inaccessible whenever the jack is positioned beneath, and is supporting the weight of a vehicle. It is often necessary for one who 25 operates the jack to reach under the car to shift the trip lever, and in many instances the conditions of the road are such that it is not only inconvenient, but even difficult to reverse the mechanism.

An object of this invention is to provide 30 means, whereby the tripping operation, to cause the reverse movement, may be quickly executed without requiring the operator to reach into an inconvenient location under the vehicle support. In accomplishing this, 35 I provide a handle of such character that the trip lever may be operated to govern the direction in travel of the rack bar, by a simple movement of the handle under control of the operator.

40 The means for accomplishing the above objects will be fully set forth in the following description, which relates to the drawings, and the essential characteristics will be set forth in the claims.

45 In the drawings, Fig. 1 is an elevation partly in section of a lifting jack embodying the features of my invention; Fig. 2 is an elevation of an operating lever; Fig. 3 is an elevation of the socket member adapted for 50 use with the bar, shown in Fig. 2; Fig. 4 is a cross section taken on the line 4—4 in Fig. 1; Fig. 5 is an elevation partly in section of

a lifting jack equipped with a modified form of my invention; Fig. 6 is a cross section taken on the line 6—6 in Fig. 5; Figs. 55 7 and 8 are details of construction for use with the modified mechanism.

Broadly, my invention embraces means associated with the handle of a jack for moving the trip lever and thereby reversing the 60 direction in travel of the movable rack bar. The invention contemplates movement of the trip lever, by manipulation of the handle in a different manner from the ordinary movement required for raising the rack bar. I 65 have shown two types of movement for engaging the trip lever, one type involving the rotation of the handle and the other comprising a longitudinal movement of the handle. The means employed for reversing the 70 lever with each type will be hereinafter set forth, but a preferred form is embodied in Fig. 1, and employs a rotation of the handle.

Designating the parts shown in the drawings by the use of reference characters, 10 75 80 represents a base member of a lifting jack having a rack bar 11, and having raising mechanism carried by the frame 17 behind the plate 14 and operable by the handle 12. This invention does not contemplate any particular type of raising mechanism, but it is concerned with means for reversing the raising mechanism, and for purposes of illustration, I have shown a reversing lever 18 pivoted at 19 to the frame, and provided 85 with an outwardly extending arm 20. As usual in this type of jack, when the external end of the trip lever is up, the pawls or other internal mechanism operate to raise the rack bar when the handle is oscillated; when the 90 trip lever is moved down the internal mechanism is thereby shifted to enable oscillations of the handle to lower the load.

The arm 20 on the trip lever 18 extends outwardly from the frame, and on one side 95 of the pivot point 19, to such an extent that it may be conveniently grasped by an operator and moved manually, as usual, to reverse the raising mechanism. The mechanism for moving the trip lever automatically by the operation of the handle is adapted to cooperate with the arm 20, and, as shown in Fig. 1, the preferred form embodies one or more projecting members or

wings 21, 22, which are adapted to be moved by an operator to engage the arm 20 and thereby rotate the trip lever 18. These engaging wings 21, 22 are preferably positioned on the exterior part of a socket member 23, which member is provided at one end with the recess 24, adapted to receive the handle 12, and at the other end with a recess 25, adapted to receive and to be complementary with the plug 26, carried by the operating member 13. The plug 26 may be provided with an annular recess 27 on the exterior part of the plug. This recess serves as a guideway for a projecting member, 15 preferably a cap screw 28, which extends through the socket member 23, and is adapted to slidably engage the bottom of the recess 27 to permit the socket member to be rotated about the plug, while preventing 20 the handle being moved longitudinally of its axis.

In Fig. 1, the trip lever is shown in one position in full lines, and in another position in dotted lines. In the full line position the trip lever is about to be engaged by the projecting wing 21, and on the lower surface of the arm 20; while in the dotted position the wing 21 is shown in engagement with the upper surface of the arm 20.

In normal operation the trip lever is set in a position, necessary for the desired direction of travel, and the socket member is so turned with relation to the plug 26 that the wing members 21, 22, will not engage the projecting arm 20 at any time during the vertical movement of the handle. Should the operator desire to shift the trip lever it is only necessary for him to partially rotate the handle, and to bring one of the engaging wings into contact with the projecting arm. A continued vertical movement of the operating handle will thereby cause the projecting arm to be moved and the trip lever to be shifted. After the trip lever is moved, the handle 12 is again turned until the projecting wings are disengaged from the arm 20; whereupon further movement of the operating handle reverses the direction of movement of the rack bar 11.

From the foregoing description it will be seen that the raising mechanism may be reversed by a rotation of the operating handle, preferably through an angle of not more than 180° , and that this rotation may be effected from the end of the handle remote from the jack.

I will now describe a modified form of mechanism for reversing the trip lever, which mechanism is operated by a longitudinal movement of the operating handle.

In Fig. 5 I have shown a fragmentary elevation wherein a frame 17^a is provided with a trip lever 18^a and an operating member 13^a. The frame, lever, and operating mem-

ber, are shown in substantially the same position as those shown in Fig. 1 and are employed for the same purpose, namely, the raising of the rack bar 11^a. The projecting arm 20^a on the trip lever is adapted to be operated by a wing 30, which may extend outwardly from the socket member 31 and may be of such length that it will engage the arm 20^a when the socket member is moved inwardly and longitudinally of its axis. Normally the wing member 30 is so positioned with relation to the operating member 13^a that the wing will not engage the trip lever arm when the operating handle 12^a is moved vertically.

To maintain the wing at the required distance from the operating member, I provide a compression spring 32, which is adapted to be contained within the hollow plug 33. One end of the spring is adapted to abut the bottom of the recess in the plug 33, as 85 at 34, while the other end of the spring is adapted to abut the bottom of the recess, as at 35, in the socket member 31.

The socket member 31 is slidably mounted on the plug 33 and movement of the socket member may be regulated by a cap screw 36, which engages a rectangular notch 37. This cap screw extends through the socket member and has a portion 38 thereof which extends, into the notch 37, an amount sufficient to permit the screw to engage either the shoulder 39 or 40, and to limit the longitudinal movement of the socket member 31.

The lever 18^a may be provided with a lug 50 positioned on the inner side of the arm 20^a and near the outer end thereof. This lug is preferably integral with the arm and may be cast thereon, and may have one face thereof adapted to be engaged by the wing 30, as at 52, whenever the operator desires to raise the reversing lever 18^a. Obviously, the range in movement may be so regulated that the wing 30 is adapted to abut the lower face of the arm 20^a, but I have shown both the arm and the handle in 110 such position that it is advisable to have the wing engage some portion of the arm, as the cam surface 50.

To bring the wing into the position shown in full lines in Fig. 5, it is necessary for 115 the operator to force the handle 12 inwardly, against the spring 32, until the wing engages the lower surface of the lug on the trip lever arm. An upward movement of the handle will then throw the trip 120 lever into the position shown in dotted lines, whereupon a release of the inward pressure will permit the wing to return to normal position. On the ensuing downward motion, the wing will clear the end 125 in the projecting arm 20^a. Since only one wing 30 is employed to move the trip lever, it is necessary for the mechanism to be

so arranged, that the socket member 31 may have a greater range of movement than the trip lever.

The operation of the modified embodiment is as follows:

The trip lever is set for a raising position, before the jack is inserted beneath the object to be raised, and the handle is oscillated vertically in the customary manner 10 until the desired height is attained. To reverse the direction of the jack, the handle is urged inwardly against the force of the spring 32, the wing 30 engages either the upper or lower edge of the arm 20^a. 15 Then, when the handle is again moved vertically, the trip lever is urged in the same direction and the raising mechanism is reversed. The inward pressure on the handle is then released and the spring 20 forces the wing 30 away from the projecting arm 20^a, and further vertical movement of the handle operates to lower the rack bar 11^a.

From the foregoing description it will 25 be seen that I have provided a mechanism for reversing the raising mechanism by means co-operating with the handle and adapted to engage the trip lever by selective movements of the handle under control of the operator. Furthermore, I have provided a means of such character for reversing the trip lever that one may effect the desired direction of the rack bar movement without being compelled to reach under a vehicle, or inconvenience himself in 30 any manner.

Having thus described my invention, I claim:

1. In a lifting jack, the combination with 40 a raising mechanism, of a reversing device movable independently of the raising mechanism for determining the direction of actuation of said jack by its position and a member for operating the jack, said member being secured to the jack and serving 45 for setting the reversing mechanism.

2. In a lifting jack, the combination of a 50 raising mechanism, of a reversing device movable independently of the raising mechanism for determining the direction of actuation of said jack by its position, an operating member, and means rotatably mounted on said operating member and movable thereby for moving the reversing 55 device for actuating the same.

3. In a lifting jack, the combination of a 60 raising mechanism, of a reversing device movable independently of the raising mechanism for determining the direction of actuation of said jack by its position, an operating member, and means rotatably mounted on said operating member and movable thereby for moving the reversing device to the desired position, said means

including a member for operating the raising or lowering mechanism. 65

4. In a lifting jack, the combination with raising mechanism, of a vertically movable handle, a reversing lever, and means for setting the reversing lever, said handle being secured to said means, said means being operable to engage the lever, by movement of the handle, other than vertical movement, and be disengaged therefrom during actuation of the jack. 70 75

5. In a lifting jack, the combination with raising mechanism, of a pivoted member co-operating therewith, a reversing member, a vertically operable handle in engagement with the pivoted member and secured thereto, and an arm carried by the handle and adapted to engage the reversing member, whereby further vertical movement of the handle shifts said reversing member, to thereafter actuate the jack in the direction determined by the position of said member. 80 85

6. In a lifting jack, the combination with raising mechanism, of a pivoted operating member therefor, a vertically movable handle, means comprising a plug and socket connection, for engaging the member with the handle, a reversing lever, and an arm carried by one of said members and movable therewith for engaging the reversing 90 95 lever to reverse its position while the handle remains in engagement with the operating member.

7. In a lifting jack, the combination with raising mechanism, of a pivoted operating 100 member therefor, a handle movable vertically and relatively to said member, a reversing member and means carried by the handle, and adapted to be brought into engagement with the reversing member to reverse its position by movement of the handle 105 relatively to the operating member, the handle remaining in engagement with the operating member during the reversing action.

8. In a lifting jack, the combination with 110 raising mechanism, of a reversing member movable independently of the raising mechanism cooperating therewith, a handle mounted for rotation while connected in the socket and means operable upon rotation of the handle for engaging the reversing member. 115

9. In a lifting jack, the combination with raising mechanism, of a reversing lever 120 movable independently of the raising mechanism, a pivoted operating member, a handle rotatably mounted thereon, said handle being movable vertically for operating the raising mechanism, and means carried by one of said members for engaging the reversing lever upon rotation of the handle while in the socket. 125

10. In a lifting jack, the combination with

- raising mechanism, of a pivoted operating member, a member rotatably mounted thereon, said last mentioned member being movable vertically for operating the raising mechanism, a reversing lever movable independently of the raising mechanism, and means carried by one of said members for engaging the reversing lever upon rotation of the handle while in the socket.
- 10 11. In a lifting jack, the combination with raising mechanism, means for actuating said reversing lever, a pivoted member for operating said raising mechanism, a socket member in engagement with the pivoted member, one of said members having a recess, and the other of said members having a shank complementary with said recess, and means carried by one of said members and adapted to be brought into engagement with the lever upon rotation of the said member.
- 15 12. In a lifting jack, the combination with raising mechanism, of a reversing member, an operating lever connected with the raising mechanism, said lever having a cylindrical shank thereon, a handle having a recess therein, means for rotatably securing the handle to the lever, an arm carried by the handle and adapted to clear the reversing member during the normal raising operation, said arm being adapted to engage the reversing member when the handle is rotated, whereby further movement of the handle shifts the reversing lever.
- 20 13. In a lifting jack, the combination with raising mechanism, of a pivoted lever therefore, a reversing member cooperating with the raising mechanism, said lever having a cylindrical shank, a handle having a recess complementary to the shank, means for permitting the handle to be rotatably mounted upon the shank, said means comprising an annular recess in the shank, and a co-operating member in the handle, and means carried by the handle and adapted to be brought into engagement with the reversing member upon rotation of the handle.
- 25 14. In a lifting jack, the combination with raising mechanism, of a reversing member, an oscillating lever connected with the raising mechanism, said lever having a cylindrical shank thereon, a recessed socket member rotatably embracing said shank, a handle non-rotatably connected to the socket member, an arm carried by the socket member and adapted to clear the reversing member during the normal oscillatory operation, said arm being adapted to engage the reversing member when the handle is rotated, whereby the subsequent operating movement of the handle shifts the reversing lever.
- 30 15. In a lifting jack, the combination with raising mechanism, of a reversing lever, an operating member operable independently of the reversing lever, a means on said operating member normally inoperative when the operating member is actuated but adapted to be moved to change the position of said reversing lever to reverse the operation of said raising member upon the subsequent manipulation of said operating member.
- 35 16. In a lifting jack, the combination of a raising mechanism, a pivoted operating member, a pivoted reversing member, means on said operating member for positioning the reversing device, said means being operable independently of the raising mechanism normally out of contact therewith.
- 40 In testimony whereof, I hereunto affix my signature.

EDMUND C. BATES.
